(57) CLAIM

The ornamental design for a table-top planter with flower pockets, as shown and described.

DESCRIPTION

FIG. 1 is an exploded perspective view of a table-top planter with flower pockets, showing our new design;

FIG. 2 is a top plan view thereof;

FIG. 3 is a front elevational view thereof; and,

FIG. 4 is a bottom plan view thereof.

The broken lines depict environmental subject matter only and form no part of the claimed design.

1 Claim, 1 Drawing Sheet

FIG. 4
